Patented Feb. 16, 1915.

UNITED STATES PATENT OFFICE.

GEORGE THOMSON COLTER, OF NEW YORK, N. Y.

OVERLAP SHOWER-RING.

1,128,662.

Specification of Letters Patent. Patented Feb. 16, 1915.

Application filed May 26, 1914. Serial No. 841,140.

To all whom it may concern:

Be it known that I, GEORGE T. COLTER, a citizen of the United States, and a resident of the city of New York, borough of Manhattan, in the county and State of New York, have invented a new and Improved Overlap Shower-Ring, of which the following is a full, clear, and exact description.

This invention relates to improvements in shower rings, and has for an object to provide an improved structure wherein the curtain may be held against opening.

Another object in view is to provide a ring for a shower bath which has an overlapped portion for allowing the curtain to be overlapped at the point of opening, whereby none of the water can escape.

In carrying out the objects of the invention a shower ring is provided which has an overlapped portion. The overlapped portion of the ring may be connected or separated as desired, but must overlap to such an extent as to allow a curtain to present a substantial overlap for entirely closing the opening under all circumstances. The ring may be supported by any suitable standard, and may have a spraying device associated therewith of any desired or preferred form. Also, the entire outfit may be arranged above a bath tub or other suitable place.

In the accompanying drawings—Figure 1 is a perspective view of a ring embodying the invention, the same being shown applied; Fig. 2 is a top plan view of the ring in Fig. 1; Fig. 3 is a top plan view of a slightly modified form of the invention; Fig. 4 is a further modified form of the invention; Fig. 5 is an edge view of the structure shown in Fig. 4.

Referring to the accompanying drawings by numeral, 1 indicates a suitable standard of any desired kind through which water is passed to the distributing spraying device 2. A bracket 3 is provided on standard 1 to which is rigidly secured ring 4. The ring 4 may be of any desired shape in cross section, and also of any desired size. At any desired point around the ring, preferably opposite to the bracket 9 are arranged overlap-

ping sections 5 and 6 which have a connecting bar 7. Raised portions 8 and 9 are also provided near the ends of the sections 5 and 6 so that the end rings 10 and 11 of curtain 12 may be passed over these raised portions and thereby locked in a certain sense against any backward motion. This presents means which will hold the edges of curtain 12 in an overlapped condition as shown in Fig. 1. When the spray 2 is turned on the water cannot escape out of the curtain 12 except at the bottom. This construction is especially desirable where the shower device is arranged above a bath tub, whereby the water from the spraying device 2 will pass downwardly within curtain 12 and from thence into the tub, thus avoiding wetting the floor.

In Fig. 3 a slightly modified form of the invention is shown in which the ring 4' is provided with overlapped sections 5' and 6'. These sections are not connected as the structure shown in Fig. 2. Aside from this difference the structure is identical with that shown in Fig. 2.

In Fig. 4 will be seen a further slightly modified form of the invention in which the connecting bar 7' is raised or bowed upwardly as more clearly shown in Fig. 5.

What I claim is—

1. A shower ring comprising, a body, a pair of spaced overlapping sections, and means for connecting said sections together.

2. A shower ring comprising, a body, and spaced overlapping sections arranged at a predetermined point on said body.

3. A shower ring comprising, a body for supporting the curtain, spaced overlapping sections arranged on said body, and a raised portion arranged near the end of each of said overlapping sections whereby the curtain arranged on said body may overlap and be locked in an overlapped position.

4. A shower ring comprising, a body for supporting a curtain, a pair of spaced overlapping sections, a raised portion arranged adjacent the ends of each of said overlapping sections for locking said curtain in an overlapped position, and a connecting mem-

ber connecting the ends of said overlapping sections.

5. A shower ring comprising, a body portion, a pair of spaced overlapping sections, 5 and a bowed connecting member for connecting the ends of said overlapping sections.

In testimony whereof I have signed my

name to this specification in the presence of two subscribing witnesses.

GEORGE THOMSON COLTER.

Witnesses:
